[57] CLAIM

The ornamental design for a dispenser closure, as
shown.

DESCRIPTION

FIG. 1 is a top perspective view of a dispenser closure
showing my new design;

FIG. 2 is an inverted perspective view thereof;

FIG. 3 is a cross-sectional view thereof, taken in the
direction of the arrows along line 3—3 of FIG. 1.

FIG. 1

FIG. 2

FIG. 3
